UNITED STATES PATENT OFFICE.

MICHAEL J. KREUTZER, OF DAYTON, OHIO.

BOTTLE-WASHING APPARATUS.

Application filed November 20, 1922. Serial No. 602,191.

This invention relates to improvements in bottle washing apparatus.

The primary object of this invention is the provision of a relatively simple and compact bottle washing apparatus, which is adapted for general domestic use, including an improved arrangement to facilitate connection to an ordinary faucet.

A further object of this invention is the provision of bottle washing apparatus, including means to cleanse a bottle or other analogous article, by means of forcing granular scraping members, such as shots, into the bottle or article, under cleansing liquid pressure.

A further object of this invention is the provision of a washing apparatus of the above mentioned character including an improved arrangement for supporting and directing cleansing material into a bottle.

Other objects and advantages of this invention will be apparent during the course of the following detailed description.

In the accompanying drawing, forming a part of this specification, and wherein similar reference characters designate corresponding parts throughout the several views:

Figure 1 is a longitudinal vertical sectional view, taken through the improved washing apparatus, showing the same in use for bottle cleansing purposes.

Figure 2 is a plan view of the improved washing apparatus.

Figure 3 is a vertical sectional view, taken on the line 3—3 of Figure 1.

Figure 4 is a horizontal sectional view, taken substantially on the line 4—4 of Figure 1.

In the drawing, wherein for the purpose of illustration is shown but the preferred embodiment of this invention, the letter A generally designates the improved washing apparatus which may include a body B; means C for attachment of the body B to a faucet D, or similar member; and means E associated with the body B for supporting a bottle F in cleansing position.

The body B is preferably of any approved material including a relatively large compartment or chamber 10, entirely open at the top thereof; the bottom 11 of the body B preferably providing a downwardly tapered seating surface 12 converging to a restricted entrance passageway 13 extending through the lower reduced end 14 of the

body B. This end 14 is preferably externally screw threaded for receiving the means C, as will be subsequently described. An outlet spout 16, provided with a passageway 17, extends laterally of the body B, and communicates, as to said passageway, with the compartment 10. A laterally extending flange 18 is preferably provided outwardly of the open top of the body B, and may be provided downwardly therein with a plurality of tapped recesses such as shown at 19. A screen 21 is preferably provided over the extreme lower end surface of the body portion 14, transversely across the passageway 13, and affixed to the body B in any approved manner, whereby the granulated members or shot 25 may be supported within the compartment 10, upon the seating surface 12. A screen 27 is preferably provided within the compartment 10 transversely across the passageway 17 for retaining the shot or granulated members 25 against loss through said passageway, during a bottle cleansing operation.

The means C preferably includes an elbow 30 of right angled formation, which may be internally screw threaded at its upper end for receiving the externally screw threaded portion 14 of the body B, and at its other end is preferably internally screw threaded for receiving a second reduced elbow 32; said elbows having communicating passageways therein, establishing communication with the compartment passageway 13. A nozzle connection 35 is preferably provided, which includes a portion 36 provided with a laterally extending flange 37 thereon, and being screw threaded for detachable insertion in the internally screw threaded end of the elbow 32. A swivel member 38 is preferably provided, having the lower retaining flange 39 thereon adapted for overlapping association with the flange 37 in receiving a waterproof packing 40 therebetween; the swivel piece 38 preferably being internally screw threaded for detachable connection to the screw threaded end 41 of the faucet D, which may be of any well known type. In this arrangement, the means C for connecting the body B to the faucet D is U-shaped in formation and provides a similarly shaped passageway communicating with the body compartment 10 through the restricted passageway 13.

The bottle supporting means E includes the cylindrical shaped chuck 45 which is pro-

vided with a reduced relatively short end 46 for snug seating within the top opening of the compartment 10. The annular flange 47 extends over the top flange 18 of the body B, and is preferably provided with a plurality of vertical counter bored apertures 50, whereby screws 51 or like securing elements may attach the member 45 to the body B engaging in the tapped recesses 19. The portion 52 of the member 45, extending upwardly, is provided with an opening 53 of uniform diameter, receiving therein the resilient bushing 54, which may be of rubber, having the upper lateral annular flange 55 for overlying the top surface of the portion 52 of the chuck 45. The lower end of the inserting portion 46 is preferably provided with the spider 56, having an opening 57 therethrough for slidably and adjustably receiving a length of tubing 60; such as of brass; the spider 56 adjacent the opening 57 preferably being provided with a set screw 62 for engagement with the tubing 60 in order to retain the same in a desired adjusted relation. In position, the tubing 60 extends axially upwardly above the bottle supporting means E, and depends into the bottle compartment 10, having the lower end thereof flared, as at 63, and that the passageway 64 extending longitudinally of the tube 60 is enlarged at the lower end thereof, whereby the shot or granular members 25, which are of uniform dimension, may travel longitudinally therethrough.

In operation, the improved washing apparatus A is connected, by means of the swivel 38, to the water or liquid supplying faucet or means D. The bottle F to be washed or clamped, is next inverted and the neck 67 thereof is forced into the passageway provided in the resilient bushing 54, substantially as is illustrated in Figure 1 of the drawing and providing a leak proof connection therewith. In this position, the upper end of the tube 60 is inserted into the compartment 70 of the bottle F, while the bottle itself is supported in stable manner by the means E, against liability of accidental detachment from the washing apparatus A. When the operator turns the valve 71, which may be embodied in the faucet means D, the cleansing liquid, which ordinarily will be water, is forced, by pressure or draft, into the passageways of the elbows 30 and 32 and enters the compartment 10, through passageway 13'. It is an important feature of this invention that the inlet passageway 13 be approximately one-fourth the size of the outlet passageway 17, so that there is no reacting pressure, to speak of, acting on the forceful flow of water into the compartment 10. The liquid entering the compartment 10 will, of

course, incident to its pressure, force the granulated particles or shot, into the tube passageway 64, and the water in considerable quantity will enter the bottle chamber 70, and due to the means by which the same enters, eddies will be created therein, so that the water and the shot will be swirled around for cleansing the interior of the bottle, in thorough and efficient manner. The shot and water, after having pursued a certain path longitudinally through the chamber of the bottle F will, of course, drop through the neck passageway thereof, exteriorly of the directing tube 60, and fall into the compartment 10; the shot being segregated into the lower portion of the compartment 10 upon the seating surface 12 incident to gravity, while the used liquid will exit through the spout passageway 17. In this manner, the shot pursues a circuitous path, and is directed after cleansing use, into the entrance passageway 13.

From the foregoing description of this invention, it is obvious that a relatively simple, compact, and effective bottle washing apparatus has been provided, which is of general utility, in that the same may be used for domestic purposes.

Such changes in the shape, size and arrangement of parts may be made to the form of invention herein shown and described, as do not depart from the spirit of the invention or the scope of the claim.

I claim:

A bottle washing apparatus comprising a body having a compartment entirely open at its upper end and having its lower end provided with a relatively small inlet opening diverging into said compartment, said body having a lateral exit opening therein of relatively greater dimension than said inlet opening, a U-shaped connection for attachment in said body at the inlet end thereof, said U-shaped connection being adapted for attachment to a liquid supply source, a cap member upwardly carried by said body including a spider portion depending into said body compartment providing a passageway therethrough, a tube longitudinally disposed within said compartment and adjustable in the passageway of said spider, the lower end of said tube being outwardly flared and enlarged as to its opening for disposal adjacent the inlet opening of said body, shots disposed within the compartment on the surface thereof adjacent said inlet opening, screens over the inlet and outlet openings of said body, and a resilient bottle receiving bushing disposed within said cap, a bottle when in said bushing being invertedly disposed so that said adjustable tube extends upwardly into the same.

MICHAEL J. KREUTZER.
